A. H. SKAER ET AL

VALVE OPERATING AND CONTROLLING MEANS

Filed Sept. 4, 1923

UNITED STATES PATENT OFFICE.

ARTHUR H. SKAER AND OMAR E. CLARK, OF DENVER, COLORADO, ASSIGNORS TO THE DENVER ROCK DRILL MANUFACTURING COMPANY, OF DENVER, COLORADO, A CORPORATION OF DELAWARE.

VALVE OPERATING AND CONTROLLING MEANS.

Application filed September 4, 1923. Serial No. 660,832.

To all whom it may concern:

Be it known that we, ARTHUR H. SKAER and OMAR E. CLARK, citizens of the United States, residing at Denver, in the county of Denver and State of Colorado, have invented certain new and useful Improvements in Valve Operating and Controlling Means, of which the following is a specification.

10 The present invention relates more particularly to the means for operating the controlling valve of a drill sharpening apparatus, as fully set forth in our co-pending application Serial No. 656,985, filed August 15, 1923. It may, however, be utilized for other purposes of a generally analogous character.

The object is to provide a simple operating and locking means that requires practically no thought on the part of the operator, and in which the parts are assembled in a simple and effective manner.

In the accompanying drawings,

Figure 1 is a side elevation of a drill sharpening machine, showing the operating means and indicating its relation to the parts controlled,

Figure 2 is a side elevation of the operating device, partly in section,

30 Figure 3 is a sectional view on the line 3—3 of Figure 2.

In the apparatus disclosed, a base 4 is employed, carrying relatively movable co-acting work clamping dies 5 and a fluid actuated dolly hammer 6 that operates on a drill steel clamped by the dies 5. A controlling valve for the die actuating mechanism and dolly hammer is indicated at 7, and may be of the type disclosed in the aforementioned application. The valve includes a stem 8 connected to a bell crank 9, which bell crank in turn has a link connection 10 with the crank arm 11 of an actuating rock shaft 12. This rock shaft projects from one side of the base 4, and the invention in the present case resides in the means for operating the rock shaft and thereby the valve and holding it in different positions. As above indicated this actuating means may be employed for other purposes.

A crank arm 13 is provided at one end with a split sleeve 14 that surrounds the

projecting end of the shaft and is fixed thereto by a contracting bolt 15. The outer end of the crank arm is provided with an outwardly offset hand grip 16 preferably integral with the arm 13. This hand grip has at its outer side a longitudinal slot 17 that extends across the outer end of the arm 13 and said arm 13 has a longitudinal socket 18 drilled in its outer end and intersecting the inner end of the slot 17. A holding dog 19 is pivoted, as shown at 20 in the slot 17 at one side of the outer end of the socket 18 and has a handle 21 overlying the slot 17 and movable in the same. The inner end of this dog 22 projects beyond the inner side of the arm 13 and is adapted to ride upon a quadrant plate 23 secured to the base 4. The portion 22 is slightly offset from the handle 21 and rests upon the bottom of the slot 17, leaving the handle 21 projecting beyond the grip 16 as clearly illustrated in Figure 2. This position is normally maintained by a coiled spring 24 located in the socket 18 and having its inner end fastened at the bottom of said socket by a cross pin 25. The outer end of the spring is secured by a pin 26 in a recess 27 formed in the inner side of the dog. The quadrant plate 23 has stop shoulders 28 and 29 at its ends and has an intermediate lug 30 forming a socket 31 adapted to receive the end 22 of the dog. The lug 31 is of less height than the shoulders 28.

With this construction, when the dog 22 is in the socket 31, the valve will be locked in a predetermined position. To actuate said valve, it is only necessary for the operator to grasp the grip 16 and handle 21. By pressing the two together obviously the end 22 of the dog will be disengaged from the notch 31 so that the arm 13 is swung rearwardly to any desired position until the dog 22 abuts against the stop shoulder 28. Upon a return movement the dog will again move into the notch 31 and hold the parts in their initial position.

From the foregoing, it is thought that the construction, operation and many advantages of the herein described invention will be apparent to those skilled in the art, without further description, and it will be understood that various changes in the size, shape, proportion and minor details of con-

struction, may be resorted to without departing from the spirit or sacrificing any of the advantages of the invention.

Having thus fully described our invention, what we claim as new, and desire to secure by Letters Patent, is:—

1. A swinging handle arm having an offset hand grip at one end, said arm having a longitudinal socket extending inwardly from the hand grip, a holding dog pivoted at the outer end of the arm, and a spring connected to the dog and located in the socket.
- 10 2. A swinging handle arm having an off-

set hand grip at its outer end provided with a longitudinal slot, said arm having a longitudinal socket that opens into the slot, a holding dog having a pivotal mounting in the slot adjacent to the socket, and a coiled spring in the socket engaged with the dog. 15 20

In testimony whereof, we affix our signatures.

ARTHUR H. SKAER.
OMAR E. CLARK.
